CLAIM

The ornamental design for a pick up truck, as shown and described.

DESCRIPTION

FIG. 1 is a perspective view of a pick up truck in accordance with a preferred embodiment of the present invention; FIG. 2 is another perspective view of a pick up truck in accordance with a preferred embodiment of the present invention;

FIG. 3 is a side view of a pick up truck in accordance with a preferred embodiment of the present invention;

FIG. 4 is a front view of a pick up truck in accordance with a preferred embodiment of the present invention; and,

FIG. 5 is a rear view of a pick up truck in accordance with a preferred embodiment of the present invention.

The bottom view of the vehicle is not part of the claimed design. The sides of the vehicle are mirror images of one another. The broken lines, including for the tires, the headlamps, and the grill illustrate the environment of the design and are not part of the claimed design.
